UNITED STATES PATENT OFFICE.

HARRY R. PATTERSON, OF POUGHKEEPSIE, NEW YORK, AND CLARENCE F. GILCHRIST, OF TOLEDO, OHIO, ASSIGNEES TO THE ELECTRIC AUTO-LITE COMPANY, OF TOLEDO, OHIO, A CORPORATION OF OHIO.

COMBINED TIMER AND DISTRIBUTOR.

Original application filed July 21, 1920, Serial No. 397,895. Divided and this application filed January 2, 1924. Serial No. 683,866.

This application is a division of our co-pending application, Serial Number 397,895, filed July 21, 1920.

This invention relates to ignition apparatus for internal combustion engines and particularly to that type which includes means for timing and distributing the spark impulses to the cylinders of the engine. An object of our invention is to improve the construction and operation of such apparatus, to provide for the ready accessibility of the parts, for adjustment and cleaning and to simplify the structure in general, whereby it is adapted for quantity production at a minimum cost.

Further objects of this invention relate to economies of manufacture and details of construction as will hereinafter appear from the detailed description to follow. We accomplish the objects of our invention in one instance by the devices and means described in the following specification, but it is evident that the same may be varied widely without departing from the scope of the invention as pointed out in the appended claims. A structure constituting one embodiment of our invention, which may be the preferred, is illustrated in the accompanying drawings forming a part hereof, in which:

Figure I is a top plan view of a device illustrating our invention.

Figure II is a cross sectional view of the same taken on the line II-II of Fig. I.

Figure III is a cross sectional view taken on the line III-III of Fig. II.

Figure IV is a fragmentary elevation partly in section showing the spring hook for holding down the distributor cap.

Figure V is a fragmentary sectional view of the frame and carrier plate showing the spring holding them together.

Figure VI is a disassembled view of the rotatable parts as well as the interrupter mechanism.

Figs. VII, VIII and IX are respectively top plan views of the distributor member, the cam and the interrupter mechanism shown in Fig. VI.

Fig. X is a fragmentary view of the reverse side of the interrupter shown in Fig. IX.

Figs. XI and XII are, respectively, a top

plan view and a side elevation of the frame or casing member and

Fig. XIII is a side view of the interrupter lever.

In the drawings, the same reference numerals refer to similar parts throughout the several views, and the sectional views are taken looking in the direction of the arrows at the ends of the section lines.

Referring to the drawings, we have shown a housing for the operative parts of our device, comprising a frame or casing member 5 upon which rests a distributor cap 6. The frame 5 comprises a central or bearing portion and an outer or casing portion, the former forming the bearing for the drive shaft 7 which portion is also adapted to be received in a suitable holder comprising a part of the engine or generator with which the device is used. The casing portion of the frame 5 has a flange 8 which forms a support for the distributor cap 6 and an oil hole 9 is provided in the bottom, communicating with the shaft. The flange 8 is cut away at the points 10 and 11 for purposes to be described hereinafter. An opening 12 is also provided in the bottom of the casing, the purpose of which will also be described hereinafter. Two pairs of lugs depend from the casing by means of which two hook springs 14 are pivotally mounted and these spring hooks engage at their upper ends in suitable notches 15 formed on opposite sides of the distributor cap 6. The springs 14 are constructed to snap into the notches 15 and enable the cap to be readily applied to or removed from the frame. Web portions 16 between the spring supporting lugs serve to limit the outward movement of the springs. The distributor cap 6 is constructed of suitable insulating material, preferably phenolic con-

densate product and is shown having a central terminal 17 and six surrounding terminals 17' each extending through to the inside of the cap and co-operating with the distributor finger to be described later. Electrical connections are made from the coil and the spark plugs to the terminals 17' and 17 by means of detachable connectors, one only of which is shown in Fig. II but as this forms no part of the present invention further de-

scription thereof will not be made. The central terminal 17 carries a spring pressed contact aforementioned which bears against the aforementioned distributor finger while the 5 outer end of the finger passes close to but without actual contact with each of the terminals 17'. A small opening 50 extends through the side wall of the cap near the top and a second opening is formed at the bottom 10 of the cap by cutting away a portion of the edge as shown at 51 in Fig. V at a point opposite a notch 11. The carrier plate 18 having an integral arm 19 is journaled on the frame or casing member 5 concentric with the shaft 15 7 and is adapted to have a limited rotative movement relative to the said casing, the extent of movement being limited by the width of the slot 10 through which the arm 19 extends.

20 The carrier plate 18 is frictionally retained in position on the frame by a pair of spring clips 20 which can be readily applied to and removed from the frame or casing from the exterior thereof, the use of screws and nuts 25 being thereby avoided. As will be seen from the drawing, one end of a clip engages the top face of the plate 18 while a hook at the opposite end fits a suitable depression in the frame 5. The outer end of the arm 19 is 30 shown with an aperture for connecting an operating rod or member to shift the position of the plate 18 to advance or retard the spark. Pivotaly mounted upon the carrier plate 18 by means of a post 21 is an interrupter lever 35 22 which is preferably formed of sheet metal and, as shown in Figs. VI, IX and XIII, is bent up in the general form of a trough having a back and two side portions substantially at right angles thereto. The fulcrum end of 40 the lever is provided with a bearing sleeve 23 which has flanges 24 securely engaging the two side portions. The opposite end is reduced in thickness and carries a contact point 25. Intermediate the ends of the lever are 45 two pairs of integral ears 26 which are bent over to firmly engage and hold a cam engaging block 27 which block is of a size to snugly fit between the two sides and back of the lever with an exposed portion to be engaged by the 50 operating cam. The front or cam engaging face of this block 27 is a substantially flat surface and is so dimensioned that as the cam rotates the contact is always on that surface and the surface tangent to the cam surface. 55 This, together with the shape of the cam, insures freedom from vibration and smoothness in running. By the construction described a lever of maximum strength with minimum weight of material is obtained adapting it 60 for efficient highspeed operation. A return spring 30 has one end looped around the pivot sleeve 23 with its end formed into a hook 31 to engage the back of the lever and having its opposite end formed into a loop or hook 32 65 passing around a headed post 33 carried by

the plate 18. This spring 30 is constructed with an initial flexure and it will be seen that by providing each end of the spring with a hook, one engaging the lever and the other the post 33, that movement of the lever by the 70 cam causes the spring to be not only flexed but also to be tensioned due to the winding action at the lever end.

Adjacent the contact end of the lever and adapted to cooperate therewith is what may 75 be termed the stationary contact carrying element 35. This element comprises a post 36 carrying a screw 37 having a contact point to cooperate with the contact point on the lever, the screw being held in adjustment by 80 means of a clamping screw 38 which serves to clamp two portions of the post separated by a saw-cut 39. The contact carrying element 35 has a flat base portion 40 which rests on and is secured to the carrier plate 18, being 85 separated therefrom by a plate of insulation 41. A circuit terminal 44 extends up through the opening 12 in the frame and through the plate 18, being insulated therefrom by suitable washers and sleeves and is electrically 90 connected with the base. The opposite or contact end of the base portion 40 is secured to the carrier plate 18 in a manner to permit slight adjustment of the contact member 35 about the circuit terminal 44 as a center. 95 This is accomplished by providing a somewhat elongated hole in the plate 18, shown in dotted lines in Fig. X, through which hole extends a clamping screw 45 by means of which the contact carrying element 35 may 100 be rigidly secured to the carrier plate with the stationary and movable contacts in proper alignment.

The interrupter lever 22 with its attached contact 25 and the corresponding stationary 105 contact screw 37 form with their supports what is commonly termed "interrupter mechanism", the contacts 25 and 37 being termed the "interrupter contacts". This expression distinguishes over the distributor mechanism 110 17' and 60, whereby the current is distributed to the various engine cylinder circuits.

The upper end of the drive shaft 7 is formed with an integral collar 55 adapted to take up end thrust above which extends a slightly reduced portion 56 which, as shown more distinctly in Fig. VI, is slotted to form four quadrants. The portion 56 has a tapered opening terminating in a screw-threaded hole adapted to receive a screw 57 having a 115 tapered shank to fit the tapered opening in the shaft. A cam 58 fits snugly over the slotted portion 56 of the shaft and is held thereto in any desired adjusted position by tightening the screw 57 expanding the slotted end into a firm engagement with the cam as will be readily apparent. The screw 57 has a cylindrical or fillister head 59 which serves to support and guide the distributor member 60. 120 This member is preferably constructed in the 130

form of a disk substantially dividing the interior space into two chambers and having two integral upstanding lugs 61 on its upper face which serve to position the metallic distributor finger 62. A hollow post 63 is shown imbedded in the distributor member 60 and extending through the distributor finger 62 with the upper end rolled over to form in effect a rivet to secure the distributor finger 10 in position. The distributor element 60 is also provided with a pin 65 which engages a suitable opening 65' in the top of the cam 58 to hold the distributor in proper operative position relative to the cam. 15 By reason of the above described construction, the lugs 61 and finger 62 form in effect a centrifugal fan, setting the air in the upper chamber in rapid rotation. A circulation is thereby induced, fresh air entering at the 20 lower opening 51 and air laden ozone and nitrous acid being expelled through the opening 50. In this manner the interrupter mechanism is kept substantially free from the corrosive effects of gases produced at the spark 25 gaps.

Inasmuch as the invention herein disclosed is susceptible of various other embodiments and as various changes might be made in the embodiment set forth, it is to be understood 30 that all matter described above or shown in the accompanying drawings is to be interpreted as illustrated only, and not in a limiting sense.

Having thus described our invention, what 35 we desire to secure by United States Letters Patent and claim is:

1. In a combined timer and distributor; a shaft having a split end; a cam mounted on said end; means for expanding said split end 40 to secure said cam in adjusted position, said means having an upwardly extending portion; and a distributor having an aperture to fit said portion, said aperture having a cross section approximately uniform throughout 45 its length and equal to that of the upwardly extending portion.

2. In a combined timer and distributor; a shaft having one end slit and having a tapered opening therein; a timer cam mounted 50 on said split end; a screw having a tapered portion intermediate its head and threaded portion in engagement with said tapered opening for expanding said split end into engagement with said cam; a distributor having 55 an aperture to fit over the head of said screw; and a pin connecting said cam and said distributor, said distributor being removable from the screw head independently of the screw.

60 3. In a combined timer and distributor, the combination of a casing; a power shaft rotatably mounted in said casing; a cam mounted on said shaft within the casing; a screw insertable within the end of the shaft for holding said cam in fixed position, said screw

having a head projecting beyond the shaft end; and a disc shaped distributor element removably mounted on the head of said screw whereby the casing interior is divided into two chambers. 70

4. In a combined timer and distributor, the combination of a casing; a power shaft rotatably mounted in said casing; a cam mounted on said shaft within the casing; a screw insertable within the end of the shaft for holding said cam in fixed position, said screw having a head projecting beyond the shaft end; and a disc shaped distributor element removably mounted on the head of said screw whereby the casing interior is divided into 75 two chambers; and a pin connecting the cam and distributor whereby relative motion therebetween is prevented. 80

5. In a combined timer and distributor, the combination of a casing; a power shaft rotatably mounted in said casing; a cam mounted on said shaft within the casing; a screw insertable within the end of the shaft for holding said cam in fixed position, said screw having a cylindrical head projecting beyond 85 the shaft end; and a disc shaped distributor element removably mounted on the head of said screw whereby the casing interior is divided into two chambers, the cylindrical screw head and the corresponding cylindrical 90 cavity in the distributor disc having approximately equivalent cross sectional area whereby the distributor may be readily applied and removed. 95

6. In a device of the class described, a housing; a timer and distributor mechanism in said housing; means including a disc-like member having two upwardly raised portions, a conducting member fixed to said disc-like member between said portions, said disc-like member substantially separating said housing into two chambers containing respectively said timer and distributor mechanism and ventilating openings for said chambers. 100

7. In a device of the class described, a housing; a carrier plate within the housing; a pair of interrupter contacts including a movable contact and a stationary contact; a supporting block insulated from said plate and carried thereby, said block including a base portion and a contractile bearing portion for adjustably securing said stationary contact in position; means for adjusting said block relative to said plate and a circuit terminal 105 extending through an opening in said housing and plate and secured to said supporting block adapted to permit adjustment of said block on said plate. 115

8. In a device of the class described, a housing; a carrier plate within the housing; a pair of interrupter contacts including a movable contact and a stationary contact; a supporting block carried by said plate, said block including a base portion and a contractile 120 bearing portion for adjustably securing said stationary contact in position; means for adjusting said block relative to said plate and a circuit terminal 125 extending through an opening in said housing and plate and secured to said supporting block adapted to permit adjustment of said block on said plate. 130

- tile bearing portion for adjustably securing said stationary contact in position; a circuit terminal extending through an opening in said housing and plate and secured to said supporting block forming a pivot about which said block may be adjusted on said plate, said plate having an elongated opening therein and an adjusting means extending from said block through said elongated opening.
10. 9. In a device of the class described, a housing; a carrier plate within the housing; a pair of interrupter contacts including a movable contact and a stationary contact; a supporting block insulated from said plate and carried thereby, said block including a base portion and an elongated contractable screw threaded bearing portion for adjustably securing a screw carrying said stationary contact in position; means for locking said screw in position; means for adjusting said block relative to said plate including a circuit terminal extending through an opening in said housing and plate and secured to said supporting block forming a pivot about

which said block may be adjusted on said plate.

10. In a device of the class described, a carrier plate adapted to carry a pair of interrupter contacts, one of which is pivotally mounted on said plate and the other of which is adjustably secured in fixed position relative thereto, said plate being provided with a pivot opening and an elongated opening; a contact carrying block for said fixed contact having a base portion insulated from and extending over said openings in said plate; a circuit terminal insulated from said plate and extending through said pivot opening and secured to said base, and a clamping screw extending from said block through said elongated opening in said plate to secure said block in various positions of adjustment on said plate.

In testimony whereof, we affix our signatures.

HARRY R. PATTERSON.
C. F. GILCHRIST.
